US00D782696S

(12) **United States Design Patent** (10) **Patent No.:** **US D782,696 S**
(45) **Date of Patent:** **** Mar. 28, 2017**

(54) **CONTAINER**

(71) Applicant: **ABBOTT LABORATORIES**, Abbott Park, IL (US)
(72) Inventors: **James P. Perry**, Westerville, OH (US); **Jeremy McBroom**, Columbus, OH (US); **Bryan Eliot Rolfs**, Chicago, IL (US)

(73) Assignee: **ABBOTT LABORATORIES**, Abbott Park, IL (US)

(**) Term: **15 Years**

(21) Appl. No.: **29/551,949**

(22) Filed: **Jan. 19, 2016**

Related U.S. Application Data

(60) Division of application No. 29/523,835, filed on Apr. 14, 2014, now Pat. No. Des. 751,215, which is a division of application No. 29/470,645, filed on Oct. 23, 2013, now Pat. No. Des. 733,320, which is a continuation of application No. PCT/US2013/038468, filed on Apr. 26, 2013.

(57) **CLAIM**

We claim the ornamental design for a container, as shown and described.

DESCRIPTION

FIG. 1 is a top perspective view of a container showing the new design;

FIG. 2 is a bottom perspective view of the container of FIG. 1;

FIG. 3 is a front elevational view of the container of FIG. 1; FIG. 4 is a rear elevational view of the container of FIG. 1; FIG. 5 is a right side elevational view of the container of FIG. 1;

FIG. 6 is a left side elevational view of the container of FIG. 1;

FIG. 7 is a top side plan view of the container of FIG. 1; and, FIG. 8 is a bottom plan view of the container of FIG. 1. The broken lines shown in the figures represent portions of the container that form no part of the claimed design.

1 Claim, 7 Drawing Sheets
